United States Patent

Des. 240,659
Patented July 20, 1976

240,659

COMBINED PHONOGRAPH, RADIO AND CARTRIDGE RECORDER AND PLAYER

Minol Araki, Tokyo, Japan, assignor to Yorx
Corporation, Englewood Cliffs, N.J.

Filed Nov. 8, 1974, Ser. No. 522,138

Term of patent 14 years

Int. Cl. D14—01, 03

U.S. Cl. D56—4 R

FIG. 1

FIG. 6

FIG. 2

FIG. 5

FIG. 3

FIG. 4

FIG. 1 is a top plan view of a combined phonograph, radio and cartridge recorder and player showing my new design;

FIG. 2 is a front elevational view;

FIG. 3 is a left side elevational view;

FIG. 4 is a right side elevational view;

FIG. 5 is a rear elevational view; and

FIG. 6 is a bottom plan view.

I claim:

The ornamental design for a combined phonograph, radio and cartridge recorder and player, substantially as shown.
